UNITED STATES PATENT OFFICE.

WILLIAM H. SON, OF WILKES-BARRE, PENNSYLVANIA.

SPRING SYSTEM.

1,088,738.

Specification of Letters Patent.

Patented Mar. 3, 1914.

Application filed March 26, 1907. Serial No. 364,678.

To all whom it may concern:

Be it known that I, WILLIAM H. SON, of Wilkes-Barre, Luzerne county, Pennsylvania, have invented a new and useful Spring System, of which the following is a full, clear, and exact description, reference being had to the accompanying drawings, forming part of this specification, in which—

Figure 1 is a side elevation showing one form of a spring arrangement; Fig. 2 is a section on the line II—II of Fig. 1; and Fig. 3 is a similar view showing a modification.

My invention has relation to a system of springs, and particularly vehicle springs, such as those used on automobiles, wagons, etc., the object being to provide means for absorbing or cushioning the recoil of the main spring or springs to thereby absorb or neutralize the jumping or pounding of the vehicle body in passing over rough roads, etc.

To this end, my invention consists in using a secondary or auxiliary spring in connection with a main spring, and so arranged as to come into action upon the recoil of the main spring.

My invention also consists in the novel construction, arrangement and combination of parts all substantially as hereinafter described and pointed out in the appended claim.

Referring to the accompanying drawings, Figs. 1 and 2, the numeral 2 designates a frame member, which may be a portion of a vehicle frame. 3 is a semi elliptical spring, which is secured to the support or axle 4 by the usual clip 5, and whose ends are connected to the frame member 2 to sustain the load carried by said member. 6 designates an auxiliary or secondary spring, which is connected at one end to the central portion of the spring 3, and at the opposite end to the frame member 2. This spring consists of an intermediate coil 6', from the ends of which extend the arms 6, which are respectively connected to the spring 3 and frame member 2 by means of suitable pins or bolts 7. The upper arm of the secondary spring is shown as being flattened to form a slotted portion 11, which loosely engages the upper securing bolt 7. The framework 2 is capable

of a slight normal up and down movement without bringing the secondary spring into action. Upon any movement of the frame beyond these limits, however, the end wall of the slot will engage with the bolt 7 and thereby bring the secondary spring into play. The coils 6' of this secondary spring are so wound that upward movement of the frame 2 will tend to close the coils, and therefore will bring their resistance into action to oppose such upward movement; while a downward movement of the frame member tends to open the coils so that they offer comparatively little resistance to movement in this direction. When the vehicle wheels strike an irregularity or obstruction in the road, the recoil of the main spring 3, and the consequent upward throw of the frame member 2 brings the coil 6' into action, and its resistance is opposed to such upward movement, thereby bringing the frame member gradually and easily back to its normal position. This not only avoids the disagreeable shocks to the occupants of the vehicle, but it also avoids injury to the various parts of the vehicle due to the shocks caused by violent recoils of the main springs.

In the form shown in Fig. 3, the secondary spring is shown as interposed between the two halves of an elliptical spring 8, to which its ends are secured by the clip plates 9 and pivot 10 or other suitable joint.

The advantages of my invention result from the use of the secondary spring arranged to oppose the upward movement of the main spring after it has been moved a predetermined distance, while offering little or no resistance. This secondary spring affords simple and effective means for the purpose, which can be readily applied to existing spring systems. The vehicle may be provided with any number of these secondary springs, as may be found necessary, and their location, arrangement, and manner of connection to the main springs and to the vehicle frame may be changed in various ways, without departing from the spirit and scope of my invention, since

What I claim is:

The combination with an axle, a vehicle, and a main spring supported upon the axle

and supporting the vehicle, of a supplemental spring comprising diverging arms connected by a spring coil whose tension is increased by the separation of the arms, the arms being connected respectively to the vehicle and the axle, one of the connections being a sliding one, substantially as described.

In testimony whereof, I have hereunto set my hand.

WILLIAM H. SON.
